UNITED STATES PATENT OFFICE.

JOHN M. WARD, OF PHILADELPHIA, PENNSYLVANIA.

COUNTING-MACHINE.

No. 895,703.

Specification of Letters Patent.

Patented Aug. 11, 1908.

Application filed June 15, 1907. Serial No. 379,211.

To all whom it may concern:

Be it known that I, JOHN M. WARD, a citizen of the United States of America, residing at Philadelphia, in the county of Philadelphia and State of Pennsylvania, have invented new and useful Improvements in Counting-Machines, of which the following is a specification.

This invention relates to counting machines designed more particularly for use in counting napkins, towels, and other small articles in a laundry, and one of the principal objects of the invention is to provide a machine of simple construction which can be readily used by a person making up packages of laundry work, and which will give an accurate account of the numbers of towels or napkins contained in each package.

Another object of the invention is to provide a counting machine in which a lever is operated for each article to be counted, said lever moving a wheel to actuate an indicator, and to strike a bell at each revolution of said wheel.

These and other objects may be attained by means of the construction illustrated in the accompanying drawing, in which:

Figure 1 is a front elevation of a counting machine made in accordance with my invention. Fig. 2 is a horizontal section on the line 2—2, of Fig. 1. Fig. 3 is a vertical section on the line 3—3, of Fig. 2. Fig. 4 is a vertical section on the line 4—4, of Fig. 3, looking in the direction indicated by the arrow. Fig. 5 is a similar view on the line 5—5, of Fig. 3, looking in the direction indicated by the arrows.

Referring to the drawings for a more particular description of my invention, the numeral 1 designates a casing of suitable size and shape to contain the working parts of the counting machine, and 2 is a cover for said casing provided with a suitable latch 3. Journaled in the front and back portions of the casing is a shaft 3 comprising a key having a milled nut 4 on the outer end thereof outside the casing, and said key being fitted into a boss 5 by means of its squared end 6 which engages a similar aperture in the boss. Formed integral with the boss 5 is a sleeve 7 and a wheel 8, said wheel having a notched periphery 9 and said sleeve being mounted to rotate upon a shaft 10 secured by means of a plate 11 to the rear side of the casing 1. A ratchet wheel 12 is formed integral with the sleeve 7, and a pawl 13 pivoted to the rear

side of the casing engages the ratchet wheel 12. The sleeve 7 passes through an aperture in a partition 14. Connected to one side of the wheel 8 is a lug 15, which at each revolution of the wheel 8 comes in contact with a trigger 16 connected to an ordinary meter and indicator 17 provided with a glass plate 18 secured to the front side of the casing 1 in an opening therein through which the indicator numbers 19 may be readily seen. A finger 20 is secured to the wheel 8 and projects beyond the periphery thereof, said finger adapted to engage a bell hammer 21 at each revolution of the wheel, said hammer 70 being pivoted at 22 to the partition 14 and provided with a spring 23 for forcing the hammer against a gong 24 after the finger 20 has passed the rounded end 25 of said hammer.

A lever 26 extends through the front of the casing and is provided with a handle 27, said lever being pivoted at 28 to the end of the partition 14, and said lever being provided with an arm 29 having a lateral extension 30 having an upturned end 31 which engages a stop screw 32. Connected to the lever 26 is a rod 33 having a laterally extending end 34 which engages the teeth or notches in the wheel 8, said rod being guided by means of a support 35 secured to the partition 14 and provided with a loop through which the rod 33 passes.

The wheel 8 is provided with fifty teeth and upon one side of the wheel near the periphery thereof is a series of numerals, one for each tooth and numbering consecutively from one to fifty. Side openings 36 are formed in the front side of the casing through which the numerals on the wheel may be seen.

The operation of my invention may be briefly described as follows: In counting a quantity of napkins or towels the handle 27 is struck by the operator with the hand holding the napkin or towel while in the act of placing them on a pile, once for each movement of the lever 26. When fifty articles have been thus counted, the gong 24 is struck by the hammer 21, and this package of 105 articles is removed and another started in the same way. At the end of the counting when less than fifty remain, the number will be indicated through the eight openings 36.

From the foregoing it will be obvious that 110 a counting machine made in accordance with my invention is of comparatively simple con-

struction, cannot readily get out of order, is accurate and efficient in use and can be produced at comparatively slight cost. When it is desired to return the wheel 8 to zero, the 5 milled head 4 of the key 3 is operated.

Having thus described the invention, what I claim is:

In a counting machine, a casing, a tubular shaft, a notched wheel, and a ratchet wheel, 10 all cast in a single piece and mounted in said casing, said shaft being provided with a boss having a recess therein, a key journaled in the casing and engaging the recess in the boss, a pawl for engaging said ratchet wheel, 15 an operating lever having its end bent and

engaged by a stop, a rod connected to said lever and having its end bent to engage the teeth of said wheel, a lug secured to said wheel, a bell hammer and bell, said hammer lying in the path of said lug, a second lug on 20 one side of the wheel, a meter, and a trigger connected to said meter, said second lug adapted to engage said trigger at each rotation of said wheel.

In testimony whereof, I affix my signature 25 in presence of two witnesses.

JOHN M. WARD.
